FIG. 1

FIG. 2

FIG. 3

FIG. 4

FIG. 1 is a front elevational view of a fan showing my new design with the fan in open position;

FIG. 2 is a front elevational view thereof with the fan in a closed position; and,

FIG. 3 is a view similar to FIG. 1 but showing a modified form.

FIG. 4 is a side elevational view thereof, the side elevational view of FIG. 1 being substantially similar.

The dominant features of my design reside in the portions shown in full lines.

I claim:

The ornamental design for a fan, as shown and described.
